UNITED STATES PATENT OFFICE.

WILLIAM FRANK BROWNE, OF NEW YORK, N. Y.

PNEUMATIC PUMP.

SPECIFICATION forming part of Letters Patent No. 570,372, dated October 27, 1896.

Application filed August 15, 1896. Serial No. 602,867. (No model.)

To all whom it may concern:

Be it known that I, WILLIAM FRANK BROWNE, a citizen of the United States, and a resident of New York city, in the county 5 and State of New York, have invented certain new and useful Improvements in Pneumatic Pumps, of which the following is a specification.

This invention relates to a pneumatic pump 10 in which the piston or plunger is forced back into the raised or retracted position by means of a suitable spring.

The object of the invention is to provide a pneumatic pump which is simple in construction 15 and which is effective and durable in use.

The matter constituting my invention will be defined in the claims.

I will now describe the details of construction and operation of my improved pump by 20 reference to the accompanying drawings, in which—

Figure 1 represents a vertical central section of the pump. Fig. 2 represents an elevation of the pump barrel or cylinder, the piston or plunger being depressed and inclosed 25 within the same. Fig. 3 represents a side elevation of a slightly-modified form of pump with parts broken away.

The preferred form of my pump is illustrated in Figs. 1 and 2. The cylindrical barrel A is preferably made by drawing or spinning from a suitable piece of metal, so as to form it without seam or joint, and is provided at the top with a concave flange b and 30 at the bottom with a boss a, having a screw-threaded opening for attachment of an escape-pipe. The piston or plunger B, Fig. 1, is preferably made hollow with a cylindrical lower end and a conical upper end, or, more 35 correctly, with the upper end in the form of the frustum of a cone with a central upper opening and with the upper edge turned over to form an outwardly-projecting flange d, which is preferably concave at the under 40 side, as shown. The plunger B is hollow and has a bottom plate b'', provided near its outer edge with suitable openings a'. A disk b³ of some pliable material, such as leather, and having a turned-over edge b⁴, is secured be- 45 tween the bottom plate b'' and a metallic disk b⁵. The disk b⁵ is made of sufficient diameter

to permit the pliable edge b⁴ of the packing-disk b³ to yield and admit air between it and the wall of the cylinder into the chamber below. It will be evident that air is admitted 55 through the openings a' during the upward stroke of the plunger B. On the downward stroke of the plunger the pliable edge b⁴ will be forced against the wall of the cylinder, making therewith a tight joint, so that the 60 air will be forced out of the chamber through the perforated boss a. The upper part of the piston, which projects above the cylindrical barrel, is made conical for the purpose of permitting the spiral spring C to telescope and 65 all of its turns to lie, one within the other, in the same horizontal plane inside of the flange b, thus permitting the piston to be depressed and entirely inclosed within the pump-barrel. The lower end of the spring C is supported on 70 the flange b of the barrel and the upper end thereof bears against the under side of the flange d of the plunger. By reason of the conical form of the upper end of plunger B the pressure of the foot will be exerted thereon 75 centrally and therefore overcome the tendency of the plunger to tilt and bind, as it otherwise might if the sides were straight and the pressure was applied to one side thereof.

The piston or plunger B may be made with 80 parallel walls throughout its length, as shown in Fig. 3, and with this construction the supporting-flange b' for spring C is preferably secured a little below the top of the cylinder A. In this construction the spring C will be coiled 85 around the periphery of cylinder A and, when the plunger B is depressed, will lie in the space between the top of cylinder A and the flange b'.

The spiral or coiled spring C serves the purpose of forcing the plunger back or into a raised position after it has been depressed by the operator. By attaching a pipe to the screw-threaded boss a air may be conducted to any holder or place of use, such as a pneumatic bicycle-tire.

This pump is very light and simple in construction and well adapted to be set upon the floor or ground and operated by the pressure of the foot, applied to the top of plunger B, 100 for forcing air into bicycle-tires or other place of use.

Having described my invention, what I claim, and desire to secure by Letters Patent, is—

1. In a pneumatic pump, the cylinder or barrel, having a circumferential flange and the hollow piston or plunger having a conical upper end and an outwardly-turned flange at or near its top, in combination with an outer spiral spring interposed between and bearing on said flanges and the coils thereof lying adjacent to said conical portion of the plunger, substantially as and for the purpose described.
2. In a pneumatic pump, the cylinder or barrel, having a circumferential flange at, or near, its top and the hollow piston or plunger having a conical upper end, provided with an

outwardly-turned flange; and with a perforated bottom plate, a clamping-disk and an interposed pliable packing-disk having an inwardly-turned edge, in combination with the spiral spring C, interposed between and bearing upon said flanges on the cylinder and plunger, and lying adjacent to the conical portion of the plunger, substantially as and for the purpose described.

In testimony that I claim the foregoing as my invention I have signed my name, in presence of two witnesses, this 14th day of August, 1896.

WILLIAM FRANK BROWNE.
